UNITED STATES PATENT OFFICE.

JOSÉ MARQUES, OF GLOUCESTER, MASSACHUSETTS.

STABILIZING APPARATUS FOR AIRCRAFT.

1,277,452.

Specification of Letters Patent. Patented Sept. 3, 1918.

Application filed November 4, 1916. Serial No. 129,580.

To all whom it may concern:

Be it known that I, JOSÉ MARQUES, a subject of the King of Spain, residing at Gloucester, in the county of Essex and State 5 of Massachusetts, have invented new and useful Improvements in Stabilizing Apparatus for Aircraft, of which the following is a specification.

This invention relates to stabilizing apparatus for air craft, and one of the objects of the invention is to provide stabilizing mechanism for normally maintaining both a longitudinal and lateral stability, and which is governed by the movement of the 15 craft out of a balanced position to restore it to a state of complete equilibrium.

A further object of the invention is to provide a stabilizing apparatus operative by primary controlling elements influenced by 20 the force of gravity in the tilting of the craft upon its axes for governing the supply of compressed air for the actuation of fluid pressure operated devices, such as cylinders and pistons, for transmitting motion to aile- 25 rons or other stabilizing elements.

A still further object of the invention is to provide a stability mechanism operating in conjunction with the hand controls of the machine so that, while the machine is 30 normally controlled and its stability maintained by the automatic mechanism, the aviator may at any time assume control for manually operating the balancing elements for steering, balancing and banking pur- 35 poses, as well as for performing various evolutions in the air.

With these and other objects in view, the invention consists of the features of construction, combination and arrangement of 40 parts hereinafter fully described and claimed, reference being had to the accompanying drawings in which:—

Figure 1 is a front elevation showing the application of the invention to so much of 45 a flying machine as is necessary to illustrate the invention.

Fig. 2 is a side elevation of the same.

Fig. 3 is a vertical longitudinal section 50 on an enlarged scale through a portion of the machine.

Fig. 4 is a sectional plan view looking down upon the steering and stabilizing elements.

Fig. 5 is a vertical longitudinal section 55 through one of the compressed air operated actuating devices.

Fig. 6 is an enlarged sectional view through the steering column and related parts.

Fig. 7 is a diagrammatic perspective view 60 of the stabilizing and steering devices.

In the illustrated exemplification of the invention I have shown the application of my improved steering and stabilizing mechanism to a biplane flying machine of the heavier-than-air class, although it is to be understood that this is made simply for the purposes of disclosing one mode of carrying my invention into practical effect, and that the invention may be employed upon air 70 craft of any of the various kinds in use.

Referring now more particularly to the drawings, 1 designates the body, comprising a frame and supporting surface, of an aeroplane or other air craft embodying my invention, which may be provided with any suitable type of launching and alighting base. This craft is shown in the present instance as provided with a driving propeller 75 2 suitably driven from a motor 3 which may actuate an air compressor pump 4 suitably connected to supply compressed air to the reservoir 5, in which the air is stored and maintained at a predetermined pressure for supplying compressed air as required to the 80 actuating devices of the stabilizing elements. It is, of course, immaterial to the invention whether the air be supplied to the reservoir by means of a pump actuated by the driving motor of the air craft, or stored therein 85 by an auxiliary compressor plant, either carried by the craft or forming part of the equipment of a hangar or service station. If, as shown, the compressor pump is mounted upon the craft and driven by the 90 motor, suitable automatic means, such as is common in air brake mechanism, influenced by pressure in the tank, may be provided for throwing the pump into and out of operative connection with the motor to 95 maintain a given pressure at all times in the reservoir. I have not deemed it necessary to enter into the details of construction of 100 such an automatic air pump mechanism, however, as the same specifically constitutes 105 no part of the present invention, and as known devices for the purpose may be employed.

Pivottally mounted at the front and rear of the body, to tilt vertically on horizontal 110 transverse shafts or axes 6 and 7, are front and rear combined horizontal rudders or

elevators and longitudinal stabilizing elements 8 and 9, each comprising a plane of suitable form and construction for the purpose. These planes are connected for operation, as hereinafter described, so as to tilt in opposite directions in unison, and each plane is so mounted that when tilted to a positive angle of incidence it will exert a lifting effect and when tilted to a negative angle of incidence, it will exert a depressing effect. At opposite sides of the craft are arranged horizontal transverse shafts 6', and 7' on which are mounted lateral balancing, or stabilizing elements 8' and 9', each comprising a plane preferably of greatest length in a longitudinal direction, or parallel with the line of flight of the machine. These two planes 8' and 9' are also mounted and connected to simultaneously tilt or swing on their horizontal transverse axes in opposite directions, and each is so mounted as to exert a lifting effect when tilted to a positive angle of incidence and to exert a depressing effect when tilted to a negative angle of incidence. Suitably mounted upon the body is a vertical rudder 10, designed to perform the usual functions of a rudder of this type.

I provide means for both automatically and manually controlling the front and rear longitudinal stabilizing elements and planes, for also automatically and manually controlling the lateral stabilizing elements or planes, and for manually adjusting the vertical rudder. All of these elements are actuated from a single or common steering post or column, which includes a series of concentric shafts, constructed and arranged as hereinafter described. The lateral and longitudinal stabilizing elements are automatically and manually operable through combined gravity and compressed air and manual controls which are of similar construction, and hence a specific construction of one will generally suffice for both. In the following description I have set forth specifically the construction of the longitudinal stability controls, employing certain designating numerals of reference to indicate the parts thereof, and corresponding parts of the lateral stability controls are indicated by primed numerals of reference of the same character, from which an understanding of both structures will be obtained without the necessity of separately describing them both. Mounted upon the shafts 6 and 7 are pulleys 11 and 12 on which are respectively wound the looped portions of continuous cables 12' and 13, the cable 12' being provided with branches 14 and 15 and the cable 60 13 with branches 16 and 17.

The free ends of these cables respectively pass through sets of front and rear guides 18 and 19 at the front and rear corners of the oppositely extending arms of a control lever 65 20 loosely mounted to swing in a longitudi-

nal direction upon the central post or shaft 21 of the steering column, which post or shaft is suitably journaled at its lower end upon the body 1 and provided at its upper end with a hand wheel or manually operable control device 22'. The respective ends of the branches 14 and 15 of the cables 12' are connected with and wound in opposite directions upon one of the pulley surfaces of a double pulley 23, while the free ends of the 70 respective branches 16 and 17 of the cable 13 are similarly connected to and wound in opposite directions upon the other pulley surface of said double pulley 23. Between the sets of guides 18 and 19 and the pulley 75 23 the corresponding right and left hand branches of the cables extend over the arms of the lever 20 in a crossed relationship, the construction and arrangement of the cable branches being such that in the swinging 80 movements of the lever 20, which turns independently of the pulley 23, the extremities of the cable branches which are attached to the pulley will remain fixed, while the crossed portions of said cable branches will 85 be drawn upon or relaxed by the directions of motion of the guides 18 and 19 through which they pass, whereas when the shaft 21, to which the pulley is keyed or otherwise 90 fixed is turned, the ends of the cables will be wound and un wound according to the direction of turning motion of the shaft and their mode of connection with the pulley, allowing separate automatic or manual control actions, as I will now proceed to describe. In the automatic control action of the lever 20 in its swinging movement in one direction, assuming that the right hand arm of said lever moves rearwardly and its left hand arm forwardly, it will be evident that 95 one of the branches of the cable 12' will be drawn upon by its guide 18 and the other relaxed by the relaxation of pressure thereon by its guide 18, and that when the arms of the lever 20 move in the reverse directions 100 the motions of said cable branches will be reversed. Similar actions of the branches of the cable 13 take place when the arms of the lever with which they are in guided connection move forwardly or rearwardly, one 105 cable branch being drawn upon and the other relaxed to effect a tilting motion of the balancing plane controlled thereby in one direction or the other. On the other hand when the shaft 21 is turned in one direction or the other the lever will remain substantially fixed while the cable branches will wind about or unwind from the pulley 23 through their mode of connection therewith and the direction of turning motion of 110 the pulley, and will run through the guides 18 and 19 in such controlling actions. The 115 adjustments of the balancing planes obtained by the aforesaid operations of the lever and pulley will be readily understood by refer-

ence to the drawings, and particularly Fig. 7, so that specific description thereof will be unnecessary, it being evident, however, from the foregoing description that the planes 5 may be separately controlled by the automatic and manually operable control devices without interference each from the other.

The steering column includes in addition to the lever 20, shaft 21', control wheels 22' 10 and double pulley 23' of the corresponding parts of the control mechanism of the lateral balancing planes, a control shaft 24 provided with a hand wheel 25 and a pulley 26, all of which shafts and pulleys are 15 concentrically mounted and arranged to be operated without interference. Wound in opposite directions about the pulley 26 is the central portion or bight of a cable 27, the ends of the branches of which are suitably connected to the vertical rudder 10 so 20 that reverse motions may be communicated to said rudder on reverse motions of said pulley through its actuating shaft and hand wheel. It will thus be seen that all of the 25 manually operable parts of the control mechanism are arranged to be easily and conveniently operated from a common point, which may be in proximity to the aviator's seat, and it will, of course, be understood that in practice suitable means 30 may be provided for independently locking any of the control elements against motion when desired, or the hand controls may be arranged to coöperate with any suitable 35 means for maintaining them in a set position against casual displacement out of such position.

The automatic means for actuating the lever 20 comprises a fluid pressure cylinder 40 28 and piston 29 operating therein, said piston having its rod 30 connected with one of the arms of said lever. The opposite ends of the cylinder are provided with combined inlet and exhaust ports 31 and 32 communicating with the lower ends of combined 45 supply and primary exhaust pipes 33 and 34 connected at their opposite ends with a valve casing 35 in which is a rotary controlling valve 36 movable to opposite positions for alternately connecting said pipes 33 and 34 with a fluid pressure supply pipe 37 and a final exhaust pipe 38. The pipes 33, 34, 37 and 38, together with the valve casing 35, are supported upon a standard 50 39 carried by the cylinder 28, which cylinder is pivotally mounted at one end, as indicated at 39, upon a stationary platform 40 fixed to the frame of the machine and which also serves as a bed for the motor 60 and deck on which the steering column is mounted, the opposite or free end of the cylinder being provided with a wheel or roller 41 to allow it to swing in an arc upon the platform so that the piston and cylinder 65 may accommodate themselves to the

angularity of motion of the arm of the lever 20 to which the piston rod is attached. The valve 36 is provided with an outwardly projecting stem to which is attached a weighted pendulum rod or lever 42 limited 70 in its movements by stops 43. When the craft is in a longitudinally balanced position the weighted lever 42, which always maintains a vertical position, holds the valve 36 in a neutral position, thus cutting 75 off communication between the supply and exhaust pipes and the pipes 33 and 34, but when the craft tilts longitudinally in one direction or the other the valve is moved in one direction or the other to permit air 80 from the supply pipe to pass to one end of the cylinder and air to exhaust from the opposite end of the cylinder, whereby the piston will be moved in one direction or the other to apply controlling motions to the 85 lever 20. It will thus be apparent that the lever 20 will be operated automatically in one direction or the other by the gravity controlled fluid pressure mechanism to adjust the front and rear balancing planes to 90 restore the craft to a state of balance or equilibrium. In such movements of the lever, as above stated, the piston and cylinder will swing in an arc to accommodate 95 themselves to the arc of motion of the lever. For the purpose of permitting such motion it will, of course, be understood that the pipe 37 will be flexibly connected in any suitable manner with the air reservoir. From the foregoing description pertaining 100 to the automatic control mechanism of the longitudinal balancing elements, the operation of the automatic control mechanism of the lateral stability planes will be readily understood from the foregoing description, 105 the only essential difference in the two sets of devices being that the fluid pressure controller of the lateral balancing elements is arranged for operation so as to be governed by the lateral tilting movements of the 110 craft.

While I have specified, and shown for purposes of exemplification, the use of stabilizing elements in the form of planes, it will, of course, be understood that any 115 suitable construction of stabilizing elements may be employed, and that such other changes and modifications as fall within the scope of the appended claims may be made without departing from the spirit or 120 sacrificing any of the advantages of the invention.

I claim:—

1. In a stability controlling mechanism for aeroplanes, stabilizing members, a 125 swinging lever for operating the same, a single fluid pressure cylinder pivotally mounted for swinging movement on a vertical axis, a piston operating in said cylinder, and operatively connected with said le- 130

ver, and gravity controlled means for supplying fluid pressure to said cylinder.

2. In a stabilizing mechanism for aeroplanes, stabilizing means, a swinging lever for operating the same, a single cylinder pivotally mounted for swinging movement on a vertical axis, a piston movable in said cylinder and coupled to said lever, means for supplying fluid pressure to and exhausting the same from opposite ends of the cylinder, and a gravity controlled element for governing said fluid pressure supplying and exhausting means.

3. In a stability mechanism for air craft, stabilizing means, a swinging lever for operating the same, a single fluid pressure cylinder pivotally mounted for swinging movement on a vertical axis, a valve mechanism for supplying and exhausting fluid pressure to and from the opposite ends of the cylinder, and a swinging gravity controlled element governing said valve mechanism.

4. In a stability mechanism for air craft, stabilizing means, a swinging lever for operating the same, a single fluid pressure cyl-

inder operatively coupled thereto pivotally mounted for swinging movement on a vertical axis, means mounting said cylinder and piston to contact the same to accommodate themselves to angularities of movement of the lever, a valve mechanism for controlling the supply and exhaust of fluid pressure to and from the ends of the cylinder, and gravity controlled means governing said valve mechanism.

5. In a stability mechanism for air craft, stabilizing means, a swinging lever for operating the same, a single fluid pressure cylinder and piston operatively coupled thereto pivotally mounted for swinging movement on a vertical axis, supply and exhaust pipes connected with the opposite ends of the cylinder, a valve casing, supply and exhaust pipes connected with said casing, a rotary valve operating in said casing, and a gravity controlled element for actuating said valve.

In testimony whereof I affix my signature.

JOSÉ MARQUES.
